AUTOMATIC SELF LOADING CONVEYER

Filed Dec. 19, 1940

UNITED STATES PATENT OFFICE

2,277,396

AUTOMATIC SELF-LOADING CONVEYER

Joseph A. Gabriel, Cleveland, Ohio

Application December 19, 1940, Serial No. 370,871

7 Claims. (Cl. 198—11)

The invention relates to self-loading conveyers, and particularly to those of the endless belt type, and may be embodied in portable elevator loaders adapted to be manually moved about on suitable wheels, or by power means, and is particularly useful in coal yards, sand and gravel plants, and for handling earth, loose materials such as wood blocks, shavings and saw-dust, in coal mines, mills and various other situations.

It is also adapted to be embodied in larger forms to be tractor propelled, for various operations where it is applicable, and may be modified to meet a large number of conditions for loading, or for excavating operations. In its present embodiment it is adapted for a modified excavating or loading operation where surface materials may be taken up from a slight depth and its modification for other uses will be readily understood.

It is an important object of the invention to provide a good, tight endless conveyer and loader device which will be liable in a minimum degree to clogging or to wear by access of grit to the operative parts. It is also an important aim to provide a loading device which is adapted to operate with high efficiency in cleaning floors or ground surfaces upon which loose material may be stacked, so that a minimum amount of material will be left in the loading operation of my invention.

It is also an important aim of the invention to enable a conveyer of the character indicated to be constructed in an extremely rugged and durable form, yet involving a minimum of weight, and requiring a minimum of power for its operation. A related advantage is to enable the construction of the machine with an extremely simple design in the operative parts and framing, to the end that a minimum of cost will be involved in the embodiment, as well as a minimum liability of derangement, and attainment of great ease in servicing and repairs.

A further aim of the invention is to present such a device which is adapted to use readily in the handling of light or heavy materials without modification. A further object is to present a novel shovel element and operative means therefor, by which scraping or excavating operations may be conducted. A further aim is to present a novel construction for the exclusion of dust from the operative parts of such a device. A further important aim is to present a novel construction of conveyer chain and mounting for shovel elements and their operation in such a device. It is also an important aim to evolve a novel combination and coordination of a belt supporting plate, belt conveyer and endless chain shovel device.

Additional objects, advantages and features of invention reside in the construction, arrangement and combination of parts involved in the embodiment.

ment of the invention, as will be more readily understood from the following description and accompanying drawing, wherein—

Figure 1 is a side elevation of a hand-propelled loader, adapted to be power-driven, and embodying my invention, portions being broken away to show positions of the shovel on the ascending and descending reaches.

Figure 2 is a fragmentary plan view showing 10 the loading end of the conveyor.

Figure 3 is a cross section on the line 3—3 of Figure 2.

Figure 4 is a cross section on the line 4—4 of Figure 3.

15 There is illustrated a wheeled truck 10, supporting an endless conveyer frame 11, which may include an electric motor power means 11' of any familiar type, not illustrated in detail but which may be incorporated at any convenient point on the frame or truck, in accordance with approved practices. If desired, handles 12 may be provided at convenient points for shifting the device, or other means provided for its moving or transportation. The weight of the conveyer 20 frame, motor and drive, may be so disposed as to cause one end to set upon the ground, called the loading end, as at 13, while the body of the frame is inclined therefrom upwardly toward a discharge end, at which a delivery spout 14 may be 25 provided, or not, as desired.

The frame work of the machine includes two main side frame members 15, of identical form except they comprise right and left members, and these have suitable bearings 16 at their upper ends and 17 at their lower ends, the latter being 30 illustrated in detail in Figures 3 and 4. As the construction of the framing and conveyer mounting and drive means are similar at each end of the frame, except for the adaptation of the loading end to engage closely upon the ground, while the discharge end has the spout 14 before described, only the mounting end construction of the parts at the loading end will be described, and operative connections with the conveyer 35 carrying sprockets and rollers may be made at either or both ends, in accordance with approved practices in such appliances, these details being 40 not illustrated, since they comprise no new or novel feature of my invention.

45 Each of the side members 15 in the present instance extends continuously from the loading end to the discharge end, but it is discretionary to omit certain guide channels and cam channels over portions of the length of these members, if desired, and is found practicable. In the present 50 instance, however, the side members are constructed to enclose an endless chain element to be described, with certain operating cranks and shovel trunnions completely, throughout the orbit 55 of these elements.

Each side member comprises a main inner, and in the present instance, vertical channel wall 18, upon the upper edge of which there is extended divergently outward aprons or hopper, plates 19, the opposed walls 18 and 19 at opposite sides of the device constituting a main conveyer channel 20. At the lower end of the frame a suitable recess 21 is formed in each side member, in which there is formed a bearing box 22, bushed to form the bearing 17, the inner portion of which stops outwardly of the plane of the wall 18 a distance, and revolvably mounted in the opposed bearings there is a main lower conveyer shaft 23.

From this recess to the upper end of the conveyer which may be correspondingly formed, there are upper and lower belt and chain accommodating channels 24, and outwardly of these in turn, a communicating cam channel 25, in a plane parallel to the wall 18, but diverging from the tangent dimension inwardly or outwardly, as the case may be, for the purposes of operation of shovel elements, also to be subsequently described. Fixed on the shaft 23 immediately adjacent the bearing 22, there is a sprocket 26, upon which a chain 27 is engaged, travelling in the channel 24, and conforming to conventional chain construction, with the exception that at proper intervals certain of the links are formed with outwardly extending lugs 27' carrying a bearing portion 28, in which there are engaged the trunnion portions 29 of rocking shovels 30 mounted in the channel 20. Inwardly of the sprocket 26 a roller cylinder 31 is fixed on the shaft 23, its periphery extending outwardly into the channel 24 a distance, so as to underlie the wall 18. Engaged snugly around the roller 31 there is an endless belt 32, and suitably mounted between the side members 15, supporting plates 33 are provided, upon which the upper reach of the belt may slide and be supported in proper form. The belt is thereby supported in close relation to the path of the shovels, as will appear. In alignment with the chain, there are upper and lower guide and support flanges 34 and 35, formed integrally on the side members 15 at the upper and lower sides of the channel 24, the flange 35 being aligned with the body periphery of the sprocket so as to receive the chain slidably as it leaves the sprockets. The links and lugs 27 may project on each side of these guide flanges and the sprocket body, so as to be retained securely in a planiform course. As before indicated, the flanges 34 and 35 with the chain are spaced slightly outwardly from the plane of the wall 18, and the latter is formed with a lower edge portion of smoothly finished face at 36, this being over and parallel to the belt. A continuous closure belt 37 is engaged between the face 36 of the wall 18 and the belt, forming a closure between the channels 20 and the channels 24, both at the upper and lower sides of the machine. The trunnions 29 pass through this belt with a suitable bearing or bushing 38 to reduce friction. The closure belt 37 may be of any suitable flexible material, and may be resistant to deterioration by oil and the like, for the purpose of preserving long life and confining oil, if desired.

The trunnions 29 project through the bearings 28 outwardly a distance, and have fixed thereon crank arms 39 which are extended forwardly in the direction of movement of the conveyer in the present instance, and have at their outer ends wiper rollers 40 set in the cam channel 25 at each side of the machine.

The shovel elements 30 are nearly or quite planiform plates, although they may be suitably tapered or otherwise shaped to improve their function and strength, in the present instance 5 their outer edges being approximately rectilinear and horizontal while their inner portions next the belt are considerably thickened and formed with a hub portion 41 substantially cylindrical, and concentric with trunnions 29 of each shovel 10 element, the blade portion 30 extending at a tangent to the hub. The arms 39 of each shovel element are extended on a radius of the hub and trunnion at a great angle to the plane of the shovel, which may be more or less, according 15 to the requirement, but in the present instance, is a little short of 90 degrees. The arms being projected forwardly in the direction of progress of the conveyer, therefore, inward or outward movement of the wiper rollers thereon will move 20 the shovel blades inwardly or outwardly, correspondingly. The cam channels 25 at the lower side of the side members 15 are located relatively close to the path of the lower reach of the belt, with the result that the shovel blades are drawn 25 upwardly to a minimum projection away from the belt. At the lower end of the machine, the channel at each side is downwardly curved, slightly, as at 42, this curve being calculated in relation to the angle between the normal 30 course of the lower reach of the belt in approaching the roller 31, and the horizontal, so that as each shovel approaches the roller 31 its outer edge is slightly raised progressively, so that its resultant movement is horizontal until 35 the axis of the hub reaches a radius of the roller 31 coincident with the beginning of the tangent on which the belt approaches the roller 31. At this point the channel 25 is divergent from a concentric path around the shaft 23, so that the 40 outer end of the shovels is moved progressively outward to a maximum projection which is approximately radial to the roller 31 a short distance outwardly of the point at which the hub of the shovel begins to move on a tangent upwardly from the roller, from which point the channel 25 is slightly convergent to the plane of the belt, so that the shovels are drawn slightly 45 inwardly again, to the angle shown at the upper side of Figure 4. From this point, the channel 25 is parallel to the belt, so that these shovels are retained in this fixed relation to the plane of the belt until they reach the upper end of the conveyer, where the channel 25 may be given a similar form in relation to the axis of the upper 50 roller of the conveyer, if desired, as will be understood from the description given. This is discretionary, and the convolutions of the channel 25 may be variously formed as required, to facilitate the discharge of material from the shovels, and to draw the shovels inwardly in close relation to the belt at its lower reach, as described.

In accordance with the movement of the shovels as last described, the vertical portion of the wall 18 may be decreased in radius toward its lower portion, to correspond to the radius of the outer edges of the shovels, as indicated at 46, and the apron portion 19 may be extended further therefrom than at the upper part, as indicated at 47, although it may be more or less extended or otherwise shaped and formed to facilitate entry of material between the side members of the machine as it is advanced, as discretion may dictate.

In the normal construction of this machine for simple loading operations, the machine is ad-

vanced with the forward end portion of the side members resting slidably upon the floor or ground surface as the material to be loaded is encountered, and it is pressed into the material piled or scattered before it and moved progressively forward while the operating motor drives the conveyer to move the upper reach upwardly between the members 15. This results in any small quantities of material scattered upon the floor or ground being pushed forward by the shovels as they move slidably at the lower portion of their path, and particles or portions of the encountered material will slide inwardly upon the shovels and be lifted thereby and carried upwardly close against the belt, the shovels forming in conjunction with the belt and the side walls 18 respective pockets in which a considerable amount of material may be held. As the machine is pressed forwardly, in case all of the encountered material is not lifted directly upon the shovels, that portion which is pushed forward in advance of the shovels as the machine moves forward, may pile up in front of the machine, and so afford a stop for the material immediately engaged by the shovels and a certain amount of that in the upper piled up portion will be lifted as the shovels move upwardly. If the machine is pressed forwardly into loose material with considerable force or speed, it will tend to pile up the material higher and result in a heavier loading of the conveyer. Should it be desired to use the device for excavating purposes, as for lifting weathered clay from a surface, the channel 25 may be correspondingly formed at its lower part to throw the blades downwardly below the side members 15 to the desired extent, so that they will scrape as deeply as is desired and lift the removed surface material to the point for discharge into a truck or dump car, as indicated formally at 48 in Figure 1. Various other uses of the machine will suggest themselves to those considering this disclosure, and it will be understood that while I have shown a specific construction and proportion of elements and mechanisms, these are purely exemplary, and various changes in construction, arrangement and combination of parts may be made without departing from the spirit of the invention, as more particularly set forth in the appended claims.

I claim:

1. A conveyer of the character described comprising a frame having side members constructed to form a channel therebetween and having rollers mounted at respective ends thereof, a supported endless belt engaged around the rollers, the side members having channels therein conforming to the path of the belt, an endless chain element mounted in said channel, sprocket mounting for the chain, said chain having a plurality of transverse bearings, shaft elements mounted in the chains at each side of the machine, blade elements on the shafts extending in close relation to the belt outwardly and rockable on said shaft elements from positions close to the belt to extended position, said shaft elements having crank arms at their outer parts, cam channels formed in the side members, and wipers on the crank engaged in said cam channels, for the purposes described.

2. The structure of claim 1 in which the side walls of said channel stop short of the belt, and endless flexible members extending between said side walls and the belt as a closure, receiving said shaft elements revolvably therethrough.

3. The structure of claim 1 in which said chan-

nels in the side member include guide flanges receiving said bearing elements of the chain slidably therebetween.

4. In apparatus of the character described, an endless belt conveyer having a receiving end, a continuous plate for support of the belt comprising side members stopping short of the outer face of the belt, and endless flexible members movable with the belt and engaged between said side members and the belt, said blades having mounting shaft elements extended revolvably through the said flexible closure elements, an endless chain mounted for movement in a path closely approximating that of the belt and having said shaft elements revolvably mounted thereon, and means to rock the shaft constructed to project the blades progressively beginning at a predetermined lower part of the movement of the conveyer belt and to retract the blades before their return to said parts of the movement of the belt.

5. In apparatus of the character described, an endless belt conveyer having a receiving end, a continuous plate for support of the belt comprising side members stopping short of the outer face of the belt, an endless flexible member movable with the belt at each side and engaged between said side members and the belt, said blades having mounting shaft elements extended revolvably through the said flexible closure elements, an endless chain mounted for movement in a path closely approximating that of the belt and having said shaft element revolvably mounted, thereon, and means to rock the shaft constructed to project the blades progressively beginning at a predetermined lower part of the movement of the conveyer belt and to retract the blades before their return to said parts of the movement of the belt, said means to rock the blades consisting of respective crank elements on said shaft elements, a cam groove in the side member of the conveyor mounting and a wiper roller on the crank engaged in the groove, for the purposes described.

6. In a machine of the class described, a plate supported endless belt conveyer, an endless chain member mounted for movement in a path closely approximating the belt, means to move the belt and chain synchronously in the same direction, a plurality of blade elements pivoted on the chain extending transversely of the belt, a cam device located close beside the path of the chain, said cam device consisting of a side member in the conveyer having a cam channel thereon, an eccentric device fixed with relation to each of the blades and having an arm extended at a considerable angle to the mean plane of the respective blade and having a wiper thereon extended laterally into said channel, the distance of said cam channel from a projection of the path of the chain being varied, whereby the wiper will swing on the axis of the said shaft element and so move the blades, and being positioned so as to retract the blades approaching a terminal portion of the conveyer and project the same for movement in a horizontal direction at their outer parts a distance, and then divergently with respect to said belt to a desired final extended position, for the purposes described.

7. The structure of claim 6 in which said blade elements are substantially planiform, shovel-like members and the conveyer device includes side members with walls closely adjacent the blades, to form a channel, whereby the blades, the plate, supported belt and said side members will form pockets, for the purposes described.

JOSEPH A. GABRIEL.
